(57) **CLAIM**

We claim the ornamental design for an inverter, as shown and described.

DESCRIPTION

FIG. 1 is a front elevational view of the inverter of the invention;

FIG. 2 is a left elevational view of the inverter of the invention;

FIG. 3 is a right elevational view of the inverter of the invention;

FIG. 4 is a top plan view of the inverter of the invention;

FIG. 5 is a bottom plan view of the inverter of the invention; and,

FIG. 6 is a front isometric view of the inverter of the invention.

1 Claim, 5 Drawing Sheets

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : D724,536 S
APPLICATION NO. : 29/492019
DATED : March 17, 2015
INVENTOR(S) : Wang et al.

Page 1 of 1

It is certified that error appears in the above-identified patent and that said Letters Patent is hereby corrected as shown below:

1. At item (73) on the Title page of the Letters Patent, please amend the city of the Assignee to remove "Wingbo" and replace it with --Ningbo--.

Signed and Sealed this
Fourth Day of August, 2015

Michelle K. Lee
Director of the United States Patent and Trademark Office
